UNITED STATES PATENT OFFICE.

JAMES A. CHARNLEY, OF PROVIDENCE, RHODE ISLAND.

DESIGN FOR A BRACELET.

SPECIFICATION forming part of Design No. 14,568, dated January 29, 1884.

Application filed November 14, 1883. Term of patent 14 years.

To all whom it may concern:

Be it known that I, JAMES A. CHARNLEY, a citizen of the United States, residing at Providence, in the county of Providence and State 5 of Rhode Island, have invented and produced a new and original Design for Bracelets, of which the following is a specification, reference being had to the accompanying drawings, forming part thereof.

10 My novel design consists in a bracelet composed of a band or body of suitable material, having on either edge a strip contrasting in shade therewith, the band having ornamentations on its face at the ends, ribs on its back, 15 and a figured clasp, all as shown in the accompanying drawings.

In the accompanying drawings, Figure 1 represents a face view of the bracelet and clasp. Fig. 2 is a perspective view of the 20 same.

A designates the band, having on the face thereof at both ends the ornamentation shown at $a^2 a^2$. B represents the face of the clasp,

having ornamentation shown in the drawings at b, and having the rim or frame b'. c c represent the beaded rows on the face of the band A, extending its full length between the body of the band and the strips $a' a'$. 25

In Fig. 2, d d represent the ribs on the inside of the bracelet or on the back of the 30 band A, which extends its full length.

What I claim as my design, and desire to secure by Letters Patent, is—

The design for a bracelet, consisting of a band or body, A, strips $a' a'$, contrasting in shade 35 therewith, and ribs d d, said band being ornamented on both ends at $a^2 a^2$, and having beaded rows c c, and clasp B, having ornamentation b and rim or frame b', as described and shown. 40

In testimony whereof I affix my signature in presence of two witnesses.

JAMES A. CHARNLEY.
